UNITED STATES PATENT OFFICE.

JAMES DAVIS AND WILLIAM ARTHUR THOMAS, OF PITTSBURG,
PENNSYLVANIA.

COMBINED SWITCH, LOOP, AND CROSS-OVER FOR RAILWAYS.

SPECIFICATION forming part of Letters Patent No. 534,818, dated February 26, 1895.

Application filed November 15, 1894. Serial No. 528,937. (No model.)

To all whom it may concern:

Be it known that we, JAMES DAVIS and WILLIAM ARTHUR THOMAS, citizens of the United States of America, residing at Pittsburg, in the county of Allegheny and State of Pennsylvania, have invented certain new and useful Improvements in a Combined Switch, Loop, and Cross-OVER for Railroads, of which the following is a specification, reference being had 10 to therein to the accompanying drawing.

This invention relates to certain new and useful improvements in switches, and more particularly to a combined switch, loop and cross-over for railroads.

15 The invention is particularly applicable to street railways.

The invention has for its object a novel form of track and switches that will facilitate the traffic of street railway cars terminating at 20 one point, or at a junction where a number of lines intersect each other, a still further object of the invention being to obtain a continuous circuit of all lines at the terminal point thereby avoiding the switch-back; thus obtaining 25 a great advantage over other systems that are now in use, inasmuch as changing the direct motion of the car while traversing any portion of the circuit will be obviated.

With the above and other objects in view 30 the invention finally consists in the novel construction, combination and arrangements of the tracks and switches to be hereinafter more particularly described and pointed out in the claims.

35 Referring to the accompanying drawing forming a part of this specification the figure represents a plan view of our improved switch-loop and cross-over.

In the drawing, "1" indicates the main track 40 which is annular in form. This main circuit is provided with continuous side branches N, S, E, W, respectively; the said branches intersecting the main circuit at four points or any number of points approximately at right angles from the center of the circle.

"2" represents the switches which are of the ordinary and well known construction.

"3" represents the castings of the branches at the intersection of the main circuit.

45 The boundary of the streets is indicated by the letters N, E, and S, E, and N W and S, W.

Operation: It will be noted that a car when on the main circuit may be easily transferred to any of the branch lines. For the purpose of illustrating this let us suppose that a car is 55 running on the right hand side of the "S" track in a direction toward "N" or north. Supposing further that the said car were to take an eastward course; the switches would then be thrown so that the car could not make 60 the circuit but would be switched in the desired direction. If the car should take a north- 65 erly course, the switches would be opened on the branch line "E," and the car allowed to traverse a portion of the circle to a point where the switch would be again closed and accomplish the desired end, i. e., to switch the car on branch "N". Should a westerly course be pursued the car would pass both the branches "E" and "N" the switches being 70 open and thus be allowed to follow the westerly course. If the car is to return in the opposite direction all switches are thrown open and the car allowed to travel over the entire circuit and return via the left hand track. 75

It will be seen that the cars moving in the opposite direction as described may be transferred in the same manner; furthermore, that a number of roads running in different directions may be readily transferred by employing our system. 80

We call particular attention to the fact that our invention may be applied to any system of street railways—such as electric, cable, motor, or horse-cars—and may be applied with 85 great advantage even though the different lines terminating at one point are operated under the above described system.

The switches may be operated in any suitable manner automatically or by hand or may 90 be controlled from a switch station located at considerable height above the center of the circle.

It will be readily seen that by the practical adoption of the above described system the 95 number of switches employed are greatly reduced compared to the present methods of switching. Furthermore, the system affords advantages in points of simplicity and cheapness.

It will be seen that various changes may be made in the details of construction without

departing from the general spirit of our invention.

Having fully described our invention, what we claim as new, and desire to secure by Letters Patent, is—

1. In a combined switch, loop and cross-over, the combination of an annular track and a series of branch lines connected therewith, substantially as shown and described.

10 2. A combined switch, loop and cross-over, consisting of an annular track, and branch

lines intersecting the said annular track at right angles, and suitable switches substantially as shown and described.

In testimony whereof we affix our signatures in presence of two witnesses.

JAMES DAVIS.

WILLIAM ARTHUR THOMAS.
